His atty.

UNITED STATES PATENT OFFICE.

LEONHARD BAUROTH, OF TOLEDO, OHIO.

ADJUSTABLE ECCENTRIC.

No. 924,307.

Specification of Letters Patent.

Patented June 8, 1909.

Application filed August 3, 1908. Serial No. 446,827.

To all whom it may concern:

Be it known that I, LEONHARD BAUROTH, a citizen of the United States, and a resident of Toledo, in the county of Lucas and State of Ohio, have invented a certain new and useful Adjustable Eccentric; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates more particularly to means for adjusting the throw of plungers of punch-presses, or the like, to adapt them to operate on work of different sizes, but is not restricted to such use.

20 The object of my invention is the provision of a simple and efficient adjustment of this character, which is strong and durable in its construction, simple of adjustment and adapted, when adjusted, to positively prevent a relative turning of the adjusting parts.

25 The operation, construction, and arrangement of the parts of the invention are fully described in the following specification, and illustrated in the accompanying drawings, in which,—

30 Figure 1 is a cross-section of a crank-shaft, as along a line $x-x$ in Fig. 2, and Fig. 2 is a side elevation thereof with the eccentric blocks and encircling-strap or plunger head 35 in section as along the line $y-y$ in Fig. 1.

Referring to the drawings, 1 designates a crank-shaft and 2 the crank-pin or eccentric thereof. This pin is preferably made square in cross-section, but may be of other polygonal shape if desired, and is so disposed relative to its turning axis or shaft center 3, which falls within the perimeter thereof, that such point 3 falls nearer to each of two adjoining sides of the pin than to any of the 40 other of said sides, and nearer to one of such adjoining sides than to the other thereof, as shown.

45 A circular-block 4 is eccentrically carried by the crank-pin 2 and has its pin receiving opening of corresponding shape and size to the crank-pin to adapt it to fit closely therearound, as shown. The block 4 when used in connection with a crank-pin disposed intermediate the ends of shaft, is preferably 50 made in two sections with the dividing line intersecting the crank-pin in parallelism with

and substantially midway of two opposed sides thereof, so that each half or section receives two of the corners of the crank-pin in a manner to prevent a relative twisting of the 60 pin within the block.

5 designates the eccentric rod or plunger, which has its head or strap loosely mounted on the eccentric block and provided with the removable cap 5', which is bolted or otherwise suitably secured to the base portion of the head.

It is apparent that by offsetting the crank-pin center from the shaft center in the manner shown and making the crank-pin square 70 or of other polygonal shape in cross-section, the throw of the eccentric rod or plunger is capable of as many distinct adjustments as there are sides to the crank-pin, and also that the polygonal form of the crank-pin will 75 prevent a relative slipping or twisting of the pin within the eccentric-block, thus maintaining the parts in accurate adjustment at all times.

Having thus described my invention, what 80 I claim as new and desire to secure by Letters Patent, is,—

1. In combination, a crank-pin of polygonal shape in cross-section, a circular block eccentrically fitted thereto, and an eccentric 85 rod or plunger mounted on the block, said pin having its turning axis disposed within its perimeter and nearer to each of two adjoining sides thereof than any of the other sides and nearer to one of said adjoining 90 sides than to the other whereby the block may be shifted to as many distinct positions of adjustment relative to the pin as there are sides on the pin.

2. In combination, a crank-pin of polygonal shape in cross-section, a circular block eccentrically fitted thereto and comprising a plurality of separable sections, and an eccentric rod or plunger carried by the block, said pin having its turning axis disposed within 95 its perimeter and nearer to each of two adjoining sides of the pin than to the other sides thereof and nearer to one of such adjoining sides than to the other, substantially as described.

100 In testimony whereof I have hereunto signed my name to this specification in the presence of two subscribing witnesses.

LEONHARD BAUROTH.
